PARALLEL COMPRESSION TAP

Howard B. Gibson, Glen Ridge, N.J., assignor to The Thomas & Betts Co., Elizabeth, N.J., a corporation of New Jersey

Filed Mar. 31, 1960, Ser. No. 59,963

Term of patent 14 years

(Cl. D26—1)

Fig. 1

Fig. 2

Fig. 3

FIG. 1 is a view in perspective of a parallel compression tap, showing my new design;

FIG. 2 is a side elevation of the parallel compression tap; and

FIG. 3 is an end elevation of the same.

The opposite side and end face of the parallel compression tap not shown are substantially mirror images of those shown.

I claim:

The ornamental design for a parallel compression tap, as shown and described.
